UNITED STATES PATENT OFFICE.

GEORGE F. GODLEY, OF PHILADELPHIA, PENNSYLVANIA.

CAR-SPRING.

SPECIFICATION forming part of Letters Patent No. 259,381, dated June 13, 1882.

Application filed December 15, 1881. (No model.)

To all whom it may concern:

Be it known that I, GEORGE F. GODLEY, a citizen of the United States, resident at the city and county of Philadelphia, in the State 5 of Pennsylvania, have invented certain new and useful Improvements in Railroad-Car Springs, of which the following is a specification, reference being had to the accompanying drawings, wherein—

10 Figure 1 is an elevation of my improved car-spring. Fig. 2 is a transverse vertical section of same. Fig. 3 is a transverse vertical section of my improved car-spring, showing a nest of three springs; and Fig. 4 is an elevation of a modified form of arrangement of my invention.

15 My invention has relation to railroad-car springs, and has for its especial object to provide a nest of edge-coiled spiral springs for railroad-cars which will possess great carrying capacity, and which will adjust itself to the varying condition of a light and a laden car, so that the latter is carried by such springs just as softly and with as easy a motion when 20 empty as when laden.

25 Heretofore edge-coiled spiral springs have been constructed with a view of obtaining the greatest carrying capacity commensurate with the amount of steel used. Such springs, when 30 in service under a car heavily laden, have the effect of causing such car to ride thereon with ease and softness of motion; but as soon as such car becomes empty the pressure or weight of the load is taken off of said springs, 35 and the latter do not then form an elastic support for the car, as the weight of the empty car is not sufficient to bring the springs into service. Hence such springs then become merely rigid supports for the empty car, and 40 when the latter is exposed to travel in such state it is jolted and jarred to such extent that its frame-work and other component parts thereof become loosened and are soon destroyed and unfit for service.

45 With my improved nest of edge-coiled spiral springs the car is spring-supported at all times—i. e., when laden or when empty; or, in other words, with my improved spring, the resilient action of the latter is at all times governed by 50 the weight of the car, while with those springs just above described the resilient action of

such springs is only governed by the car when it is laden.

My invention has for its further object to provide separating and guiding pins for a nest 55 of spiral springs which will be more effective than those heretofore used.

My invention accordingly consists of a cylindrical case having a closed top and lower exterior annular flange. Upon said flange, 60 and surrounding the body of said case, is placed a spiral spring of a length, when not compressed, to project above the top of said case. Inside of the latter is placed another spiral spring, or a nest of spirals may be substituted 65 therefor and placed therein. Such construction results in a case provided with an exterior and an interior spring or springs, one of which is adapted for carrying the light or empty car and the other coming into service when the car 70 is laden. Such springs may be so constructed that the outer one will carry the unladen car and the inner one the weighted car; or, if desired, the inner spring may be so formed that the weight of an empty car will bring it 75 into service first, while the exterior spring will not begin to be compressed until the car is laden.

If an interior nest of springs be used, it is essential that such springs be held in position 80 and separated from each other. More especially is this the case when the springs forming the nest are not all of a length. To effect such guiding and separation I employ a double pin, or a pin having varying diameters or cylindrical sections of a special formation, as hereinafter more fully set forth and claimed.

Referring to the accompanying drawings, A' represent the car-bolsters, between which my improved nest of springs (shown at A²) is 90 designed to be placed. Said nest is composed of a cylindrical case, B, having a closed top, b, and a lower exterior annular flange, b'.

C is an edge-coiled spiral spring, resting on said flange b' and surrounding the case B, so 95 that the latter is within the central opening of the spring C. Such spring is of a height that it projects above the top of the case, as shown.

D is another edge-coiled spiral spring, placed 100 within the case B, as illustrated, and is held in position by a pin, a, on bolster A'. The

spring D is smaller in diameter than the spring C, and is so made that it is of greater carrying capacity than spring C. The latter, being of a proportionately large diameter, will more readily be compressed. Hence its resiliency will come into action in advance of that of spring D, so that when a car is equipped with such springs and the latter are in service a light or empty car will be carried by the spring C, the weight 10 of the car being sufficient to compress such springs nearly one-half of their limit of motion. Consequently such empty car, when so supported, will be carried with ease and softness of motion. Any concussion resulting from shocks, 15 jolting, or other cause is absorbed by the un-compressed position of said spring C.

As soon as the car is laden, then its weight, having become more than the springs C are capable of supporting, causes said springs to 20 be wholly compressed, as shown in Fig. 2, or nearly so, as shown in Fig. 3, and the weight of the laden car falls on case B, as shown; but as said case is supported by the internal spring, D, said weight falls on such spring, and it being of great carrying capacity, the weight of 25 the laden car is sufficient to compress it only one-half of its limit of motion, the remaining half of such movement—or, in other words, one-half of the resiliency of the spring—being therefore held in reserve to absorb the concussions 30 produced from jolting or jarring of the car when it travels over the uneven places of the roadway. Hence it is plainly seen that the light or empty car is carried by the springs C and the loaded car by springs D, this result 35 being obtained without danger of breaking the flange b' off of the case B, for just as soon as the car is increased in weight beyond the extent of the carrying capacity of springs C the latter close, and bolster A then rests on case B, the weight of the car being thereby transferred 40 from flange b' to case B and its supporting-spring D. The springs C then merely rest in a compressed condition between such flange 45 and bolster, as shown in Figs. 2 and 3.

When the car is emptied of its freight the bolster A rises from case B and the springs C come into service, as above described.

If desired, the inner casing-spring may be 50 made of less carrying capacity than the outer spring. In such case the weight of the empty car will be carried by the said inner spring, and when the car is laden such spring will be wholly or nearly compressed, and the flange 55 of case B will then rest upon the bolster A', and the outer spring then comes into service to support the load.

In the drawings Figs. 1, 2, and 3, I have shown the casing placed between the bolsters, A A' with the flange toward the lower bolster, A'; but such case, with its springs, may be turned upside down without altering the de-

scribed operation of the springs, as shown in Fig. 4.

If desired, a nest of two or more springs may 65 be substituted for spring D. Such arrangement is shown at E and E', Fig. 3, wherein the inner spring, E, is shorter than the outer spring, E'. These springs are held in place by pins F F, which are respectively formed upon the casing B and a casting, G, secured to or held by frictional contact on bolster A'. Said pins F are composed of two nearly-straight cylindrical sections of varying diameter, as shown at f f', the section f entering central opening of spring 70 E and section f' that of spring E', the section f, formed on casing B, being long enough to enter the upper part of the central opening of spring E when the latter and spring E' are not in a state of compression. Such construction 80 of said pins permit the latter to more effectively hold the springs E and E' in their respective positions within the casing, and also to more efficiently separate them from each other, so that the respective coils of one will 85 never touch or rub against those of the other, thereby absolutely preventing any rubbing of the coils of one spring with those of the other. Hence such springs are always in a condition for immediate use, and do not rest one against 90 the other when not in service, as has heretofore been the case.

I have described my invention as being especially adapted to edge-coiled spiral springs; but, if desired, wire or other form of bar in 95 cross-section may be employed, such wire or round-bar springs being shown in Fig. 4.

What I claim as my invention is as follows:

1. A railroad-car spring composed of edge-coiled springs, one within the other, and an interposed bearing between two opposite ends of such springs, whereby one of such springs is adapted and designed to carry the empty car, and the other to carry the loaded car. 100

2. A railroad-car spring composed of coiled 105 springs, one within the other, and an interposed bearing or case, B, of cylindrical form, flanged at b', one of said springs being of a greater or different carrying capacity than that of the remaining spring or springs, substantially as and for the purpose set forth. 110

3. The cylindrical bearing or case B for railroad-springs, having flange b', closed top b, and pin F, formed of two sections, f f', of different diameters, each such section being of the same 115 diameter or area throughout its length, substantially as shown and described.

In testimony that I claim the foregoing I have hereunto set my hand this 5th day of December, A. D. 1881.

GEORGE F. GODLEY.
